UNITED STATES PATENT OFFICE

DAVID L. WOODBERRY, OF BALTIMORE, MARYLAND

FUSE FOR RIFLE GRENADES

Application filed September 20, 1926. Serial No. 136,663.

(GRANTED UNDER THE ACT OF MARCH 3, 1883, AS AMENDED APRIL 30, 1928; 370 O. G. 757)

The invention described herein may be manufactured and used by or for the Government for governmental purposes without the payment to me of any royalty thereon.

5 The subject of this invention is a fuse especially adapted for rifle grenades.

The principal object of the invention is the provision of a fuse which will be waterproof in storage and immediately available 10 for application to a grenade without preliminary adjustments. Facility of manufacture and assembly has also been a guiding factor in the proposed design.

To these and other ends, my invention 15 consists in the construction, arrangement and combination of elements described hereinafter and pointed out in the claims forming a part of this specification.

A practical embodiment of the invention 20 is illustrated in the accompanying drawings, wherein:

Fig. 1 is a longitudinal section, partly in elevation, of the fuse assembled with a grenade body;

25 Fig. 2 is an enlarged fragmentary detail view showing the main portion of the fuse in longitudinal section.

Referring to the drawings by numerals of reference:

30 The fuse consists of a cylindrical body 5 provided at one end with a reduced portion 6 for receiving the fuse cord 7 which carries a thimble 8 in which is the detonating charge. The other end of the body is reduced in thickness and is provided with a threaded portion 9 for attachment of a closing cap 10, and in order to preserve the tightness of the joint, the threads are treated with a water-proofing compound in any ap-

40 proved manner. When the cap is in place against the shoulder 11 its base is spaced as at 12 from the extremity of the body for a purpose which will presently appear.

Grenades of this character are discharged 45 from a specially constructed grenade gun having a separate discharge orifice for the bullet of the cartridge, the grenade being propelled with the nose or fuse end foremost, or the same is discharged from a service rifle, in which instance the usual rod, not

shown, which enters the rifle barrel is attached to the base of the body.

Within the sealed casing thus formed is the firing mechanism comprising the primer 13 mounted in a tube 14 seated adjacent the 55 cord fuse 7, and the striker 15 normally retained in the opposite end of the casing. The method of retaining the striker consists in forming on the body adjacent its end an inwardly projecting annular rib 16, which 60 rib engages in a corresponding annular groove 17 in the striker to positively hold the same in safe position. Upon discharging a grenade equipped with the fuse the 65 inertia of the striker will cause it to iron out the restraining rib 16 which is free to extend into the space 12 and the striker will fire the primer, the gases from which will vent through the openings 18 in the tube 14 70 into the casing.

While the cap 10 protects the striker against accidental release during storage and transportation there may be additionally provided a pin 19 which is removed before fusing the grenade and if necessary the opening thus uncovered may serve as a 75 vent for the powder gases.

I claim:

A fuse including a body formed with an inwardly projecting annular rib, a cap threaded to the body to form a sealed casing and having its base spaced from the end of the body, a tube seated in one end of the body and provided with vents, a primer in the tube and a striker in the other end of the body formed with an annular groove for receiving the rib, and said striker protected by the cap. 80
